DESIGN FOR A POCKET LIGHTER OR THE LIKE

Harry Negbaur, New York, N. Y., assignor to H. Negbaur & Co., Inc., New York, N. Y., a corporation of New York

Application October 29, 1941, Serial No. 103,943

Term of patent 3½ years

To all whom it may concern:

Be it known that I, Harry Negbaur, a citizen of the United States of America and a resident of New York, in the county of New York and State of New York, have invented a new, original, and ornamental Design for a Pocket Lighter or the like, of which the following is a specification, reference being had to the accompanying drawing forming a part thereof.

Figures 1 and 3 are front and rear elevational views, respectively, of the pocket lighter or the like showing my new design; and

I claim:

The ornamental design for a pocket lighter or the like, as shown.

HARRY NEGBAUR.
